SASH MOUNTING

Harry G. Larson, Alameda County, Calif.

Application July 19, 1946, Serial No. 684,971

4 Claims. (Cl. 16—163)

1

This invention relates to the hinged mounting of a sash and the like in a suitable frame for movement in the frame.

The present invention relates to an improved hinge mounting for a sash or like structure in a frame so that the sash can be moved in the frame to open and close the opening provided by the frame. While hinges of this general type have been available heretofore, that which characterizes the present invention is extremely simple and rugged, quite inexpensive to manufacture, is easily installed and possesses the additional that one of the hinge structures can be utilized on either side of the sash so that it is unnecessary to make up a right-hand hinge and a left-hand hinge. In addition, the hinge can be utilized on sash of either the casement or awning type.

It is in general the broad object of the present invention to provide a hinge mounting for a sash in a frame which is simple and rugged and relatively inexpensive to manufacture.

A further object of the present invention is to provide a hinge which can be utilized for either of the right or left-hand side of a window.

The invention includes other objects and features of advantage, some of which, together with the foregoing will appear hereinafter wherein the present preferred form of hinge of the present invention is disclosed.

In the drawings accompanying and forming a part hereof, Figure 1 is a perspective view showing the lower right-hand corner of a casement type sash installed in a suitable frame.

Figure 2 is a section taken through a typical casement type sash installation in a window frame.

Figure 3 is a plan view of a hinge of the present invention.

Figures 4 and 5 are respectively sections taken through the structures shown in Figure 3 along the lines 4—4 and 5—5 showing the shoe construction utilized.

Figure 6 is an end view of a hinge mounting showing the relation between several of its components in closed position.

The hinge of the present invention includes a first strap member 11, a second strap member 12, a third strap member 13 and a shoe 14 slidably mounted upon the first strap member 11.

The first strap member 11 includes a first frame engaging portion 16 at one end thereof having a suitable aperture therein for insertion of a screw 17 to attach the member to a frame 20. At its other end, the first strap member includes another frame engaging portion 18, this portion

2

being relatively longer than the first frame engaging portion 16 to permit of the hinge mounting thereon by pin or rivet 19 of one end of the third strap member 13. The second frame engaging portion 18 of the first strap member also includes several spaced apertures in which screws 21 can be inserted to attach the first member to the window frame 20. Intermediate the frame engaging portions 16 and 18, the first strap member includes a raised portion 22, this portion extending generally parallel to the adjacent window frame and providing a track along which shoe 15 can ride.

The second strap member 12 is hinged at one end by a pin or rivet 23 to the slidable shoe 14. The second strap member also includes a plurality of apertures 24 through which are inserted suitable wood screws or the like to attach the second strap members to a rabbeted portion 26 on a sash 27. The other end of the third lever 13 is hinged by a pin or rivet 28 to the second strap member 12 intermediate the ends of the second strap member.

The second strap member is attached to the sash, the sash frame being suitably rabbeted to admit the strap member. In a casement type window, the top and bottom of the sash are rabbeted adjacent the inner corner of the sash as I have indicated at 26 in Figure 2, one of the hinged structures of the present invention being mounted at the top and at the bottom of the sash and being attached to the top and bottom of the frame. This mounting permits the windows to be moved toward and away from the frame to provide an opening of a desired extent or to entirely close the frame. The hinge mountings provided on the window are identical and it is not necessary to distinguish between right and left-hand hinges.

It will be observed, upon examining Figure 6, that the third member 13 is secured to the second member 12 on the under side thereof and that the second member is hingedly mounted upon a raised portion provided upon the top of shoe 14, as appears in Figure 4. This permits the third member to move freely over the top of the first member 11 so that the second member 12 can be positioned in a sash supporting position on either side of the first strap member 11. This permits the structure to be utilized for installation upon either side of a sash, the structure thus serving as a mounting for a sash to swing outwardly and away from the first member in either a right hand direction or a left hand direction.

Another feature of the present invention is that

the hinge mounting described permits of adjustment of the tension placed upon the sash and the degree of frictional control maintained on the window so that its opening and closing movement is opposed by a frictional force such that slamming of the window can be avoided. This is effected by providing a hole 31 intermediate the ends of the raised portion 22 in the first strap member and by providing a simple, tapered, conventional screw 32 in this hole to extend into engagement with the adjacent frame. When the screw is driven into said frame with an ordinary screwdriver, the raised portion 22 bows and is drawn toward the sash frame. It is obvious that the simple screw 32 could be replaced by any other suitable member so long as it is adapted, when passed through said hole 31 and engaged with said sash frame 20, to draw the raised portion 22 toward the sash frame and hold it in any desired tensioned or bowed position. By flexing the raised portion 22 on the first strap member from its normal position parallel to the frame, one is able to provide a desired degree of friction between the shoes 14 and the raised portions 22. To this end and to permit the structure to be utilized for installation on either side of a window, shoe 14 is so fashioned that it will pass the element 32. To effect this, the shoe is preferably made in the shape of a U, as appears in Figure 4. However, a portion 33 of the U member is fashioned to fit the first strap member snugly, ends 34 being crimped over to engage portion 22 snugly with a sliding fit while the other portion 36 of the U member is spaced above the portion 22, as will be apparent upon comparing Figures 4 and 5. The range of adjustment of strap 11 is that permitted by the spacing between the bottom surfaces of crimped ends 34 of shoe 14 which rides along raised portion 22, and the adjacent supporting surface of sash frame 20.

I claim:

1. A hinge for mounting a sash in a sash frame comprising a first strap member having a sash frame engaging portion at each end thereof for mounting said member on said frame, said first member having a raised portion intermediate said frame engaging portions extending substantially parallel to but spaced from said sash frame, means for adjusting the position of said intermediate portion relative to said frame including a recessed aperture in said raised intermediate portion to receive a screw engaged with said sash frame to draw said raised intermediate portion toward said sash frame, a shoe slidably on said raised portion and including a U shaped member having only a portion of each leg thereof crimped over the raised portion of the first member with the ends of said legs in a spaced relationship on the underside of said raised portion, a second strap member to be secured to said sash, means hingedly securing one end of said second strap member to said shoe, and a third strap member hinged to said second strap member intermediate the ends thereof and to a sash frame engaging portion on said first strap member.

2. A hinge for mounting a sash in a sash frame comprising a first strap member having a sash frame engaging portion at each end thereof for mounting said member on said frame, said first member having a portion intermediate said frame engaging portions extending substantially parallel to but spaced from said sash frame, means for adjusting the position of said intermediate portion relative to said frame including a recessed aperture in said raised intermediate portion.

ate portion to receive a screw engaged with said sash frame to draw said raised intermediate portion toward said sash frame, a shoe slidably on said intermediate portion, a second strap member to be secured to said sash, means hingedly securing one end of said second strap member to said shoe, and a third strap member hinged to said second strap member intermediate the ends thereof and to a sash frame engaging portion on said first strap member.

3. A hinge for mounting a movable sash in a fixed sash frame comprising a first strap member having a sash frame engaging portion at each end thereof for attachment on said fixed sash frame and spaced apart by a raised portion, intermediate said fixed sash frame engaging portions, extending substantially parallel to but spaced above said fixed sash frame; a shoe slidably along said raised portion and having a U-shaped portion and another portion having means in a gripping relation with said raised portion of said first strap member; a second strap member for attachment on said movable sash; means hingedly securing one end of said second strap member to the U-shaped portion of said shoe; and a third strap member hinged to said second strap member intermediate the ends thereof and on the under face of said second strap member and movable over said first strap member raised portion to either side of said first strap member; said third member having one end thereof deformed to extend below said first strap member raised portion, said one end being hinged on a sash frame engaging portion on said first strap member.

4. A hinge for mounting a movable sash in a fixed sash frame comprising a first strap member having a sash frame engaging portion at each end thereof for attachment on said fixed sash frame and spaced apart by a raised portion, intermediate said fixed sash frame engaging portions, extending substantially parallel to but spaced above said fixed sash frame; a shoe slidably along said raised portion and having a U-shaped portion and another portion having means in a gripping relation with said raised portion of said first strap member; a second strap member for attachment on said movable sash; means hingedly securing one end of said second strap member to the U-shaped portion of said shoe; and a third strap member hinged to said second strap member intermediate the ends thereof and on the under face of said second strap member and movable over said first strap member raised portion to over-lie said first strap member and to extend on either side of said first strap member; said third member having one end thereof deformed to extend below said first strap member raised portion, said one end being hinged on a sash frame engaging portion on said first strap member; said shoe U-shaped portion overlying a sash-frame engaging portion when said third and second strap members over-lie the first strap member.
